UNITED STATES PATENT OFFICE.

MICHAEL O'CONNOR, OF NEW BRUNSWICK, NEW JERSEY.

FAUCET-SCREW.

SPECIFICATION forming part of Letters Patent No. 295,794, dated March 25, 1884.

Application filed January 19, 1884. (No model.)

To all whom it may concern:

Be it known that I, MICHAEL O'CONNOR, a citizen of the United States, residing at New Brunswick, in the county of Middlesex and State of New Jersey, have invented new and useful Improvements in Faucet-Screws, of which the following is a specification.

This invention relates to improvements in that class of nozzles for cans which are composed of a cap having a screw-socket and a spout, combined with a screw fitting the socket, and having a valve at its inner end and a head at its outer end for closing or opening the inner end of the spout.

The object of my invention is to simplify the construction of such devices and reduce the cost of manufacture.

To such end the invention consists in the construction and combination of parts herein-after described and claimed, and illustrated in the accompanying drawings, in which—

Figure 1 represents a sectional view of my faucet-screw when the valve is closed. Fig. 2 is a vertical central section of the same when the valve is open. Fig. 3 is a plan or top view of the same. Fig. 4 is a section of the valve-body detached.

Similar letters indicate corresponding parts.

In the drawings, the letter A designates a metallic plate which serves to attach the screw-faucet to a sheet-metal can, and which is provided with a sheet-metal screw-socket, a, the inner end of which is enlarged so as to form a chamber, b, from which extends the discharge-spout B. The plate, the chamber, and the screw-socket are all formed out of one and the same piece of sheet metal.

The letter C designates the valve, the body of which is composed of a sheet-metal screw-stem, c, from the inner or open end of which projects a flange, d, (best seen in Fig. 4,) said screw-stem and flange being made out of one and the same piece of sheet metal. With the flange is combined a sheet-metal cap, e, which serves to strengthen the same, and on said flange is placed a packing-piece, f, of any material suitable for the purpose. The screw-stem c fits the sheet-metal screw-socket a in the plate A, and after the same has been screwed into said socket a thumb-piece, g, is soldered or otherwise secured to its closed end. The plate A is intended to be soldered

upon a sheet-metal can which contains oil or other liquid, and which is provided with an opening large enough to admit the valve C. 55 When the thumb-piece g is turned so as to open the valve, (see Fig. 2,) the chamber b is opened all round, and a free discharge of the liquid in the can through the discharge-spout is obtained. When the thumb-piece is turned 60 so as to close the valve, the packing f is drawn up tight against the inner surface of the attaching-plate A, and it is held firmly in this position.

In manufacturing the valve-body, the sheet-metal screw-stem becomes slightly tapering, the end nearest to the flange d being the largest, and as the valve is closed this large portion of the screw-stem is gradually drawn up into the screw-socket, so that the threads are 70 not liable to strip even if the valve is drawn up against its seat with great force.

The flat attaching-plate being formed in one piece of sheet metal with the elevated chamber and the screw-socket, the cost of manufacture is reduced and the screw-threads will not 75 strip.

What I claim as new, and desire to secure by Letters Patent, is—

1. The attaching-plate A, including in one 80 piece the elevated chamber b, formed directly at the inner end of the screw-socket, and the valve-seat h, and having the nozzle and the threaded valve-stem and the valve arranged to play in the socket and bear upon the seat 85 of the attaching-plate, as and for the purpose described.

2. The attaching-plate A, adapted to be secured to a can, and including in one piece of sheet metal the screw-socket, and directly at 90 its inner end the elevated chamber b and the valve-seat h, and having the nozzle B, said socket containing the screw-stem, having a thumb-piece at its outer end, and a valved inner end arranged to close over the chamber 95 b and bear against the seat on the attaching-plate, substantially as shown and described.

In testimony whereof I have hereunto set my hand and seal in the presence of two subscribing witnesses.

MICHAEL O'CONNOR. [L. S.]
